UNITED STATES PATENT OFFICE.

EDGAR W. SUMMERS, OF PITTSBURGH, PENNSYLVANIA.

RAILWAY-CAR TRUCK.

1,189,637.

Specification of Letters Patent. Patented July 4, 1916.

Application filed April 15, 1916. Serial No. 91,842.

To all whom it may concern:

Be it known that I, EDGAR W. SUMMERS, a resident of Pittsburgh, in the county of Allegheny and State of Pennsylvania, have 5 invented a new and useful Improvement in Railway-Car Trucks, of which the following is a specification.

This invention relates to side frames for railway car trucks and journal box therefor.

One object of the invention is to provide a truck side frame of the arch bar type formed as an integral casting and so constructed as to have the journal box secured directly thereto and the parts so arranged that the centers of gravity or neutral axes of the tension and compression members intersect above the center of rotation of the axle.

20 A further object of the invention is to provide a truck side frame and a journal box therefor so designed as to reduce the height of the journal box and to bring the ends of the side frame down low relative to 25 the center of the axle.

Further objects of the invention will appear from the description and claims hereinafter made.

In the accompanying drawings, Figure 1 is a side elevation of the preferred form of 30 truck side frame and journal box, the latter being shown with the lid removed; Fig. 2 is a cross section on the line 2—2, Fig. 1; Fig. 3 is a plan view of the end portion of 35 the frame and the box; Fig. 4 is a vertical transverse section through the side frame and a longitudinal section through the journal box on the line 4—4, Fig. 1; Fig. 5 is an end elevation of the journal box, showing 40 the lid in place; Fig. 6 is a side elevation of the journal box, showing the end portion of the side frame in end elevation; Fig. 7 is a longitudinal section of the side frame and transverse section of the journal box on 45 the line 7—7, Fig. 4; Fig. 8 is a plan view of one half of the lower section of the journal box; Fig. 9 is an enlarged section through the lid; and Fig. 10 is a side elevation of the end portion of the side frame and 50 a vertical section through the journal box, showing a modification.

The truck side frame is of the arch bar type and comprises the upwardly bowed or arched compression member 1 and the 55 downwardly bowed tension member 2, the latter having its central portion, as at 3,

formed on an arc of a circle or catenary curve, and with the end portions extending from said curved portions as true tangents, together with column post members 4 interposed between the spread-apart central portions of the compression and tension members. All of these parts are formed as an integral casting, such as of cast steel. The tension and compression members are of 60 flange section and preferably of a symmetrical section, such as an I-beam section, with webs 5 located horizontally and the flanges 6 extending vertically. The centers of gravity or neutral axes of these symmetrical members intersect in the united end portion, at 65 the point 7 which is directly above the center of rotation of the axle 8. The downwardly projecting flanges on the compression member and the upwardly projecting 70 flanges on the tension member are slightly widened out toward the united end portion and are united to form in effect a gusset member 9 for strengthening the end portion. The upwardly projecting flanges of 75 the compression member are also preferably widened toward the end portion, as at 6^a, to give the necessary strength because of the necessary absence at this portion of the frame of the downwardly projecting 80 flanges. The downwardly projecting flanges of the tension member, inside of the journal box position are also preferably widened and curved downwardly, as at 6^b, to form 85 a seat to receive a block against which a jack may be set for the purpose of lifting the side frame. These portions preferably are curved downwardly, as shown, to form a slightly concaved seat to prevent accidental slipping of the jack. The end portion of the said frame is provided with a 90 reentrant seat 10 for the journal box 11. This seat, and the top of the journal box are higher at the central longitudinal axis 95 of the box than at the side edges, being 100 shown as curved from side to side, in Figs. 1 and 7, and of substantially roof shape in Fig. 10, said seat and top in both forms being of symmetrical shape on each side 105 of the longitudinal axis of the journal box so that the journal box can be interchangeably used at either end of the side frame. The curved or angle shaped seats form in effect flaring shallow pedestal jaws.

In Figs. 1 to 9 the journal box seat in the 110 frame is semicircular in cross section in order that the tension member of the side

frame can be made to pass as close as possible to the journal box and thereby bring the point of intersection of the neutral axes of the tension and compression members as low down as possible directly over the center of the axle. This journal box, at least on its upper surface, is circular in cross section, and is substantially of the form of two truncated cones with their bases united at 5 the central transverse zone of the box, so that it loosely fits in the seat in the side frame and has a bearing in said seat only at its central zone, thus permitting it to rock either in a horizontal or a vertical plane, so 10 15 20 25 30 35 40 45 50 55 60 65 70 75 80 85 90 95 100 105 110 115 120 125 130

as to hold the journal box in alignment with the axle journal to compensate for inequalities of track and yielding of the truck frame. In order to hold said journal box against rotation and also displacement, the seat 10 at its central portion is provided with a recess 12, the top of which is substantially straight or horizontal from end to end, longitudinally of the side frame, and the top of the journal box at its central zone is provided with an upward projection 13 having a horizontal top and extending into said recess and having a bearing against the top thereof. This projection is slightly higher than the top of the box immediately outside and inside of the same, and is located at the central transverse zone of the box, that is to say, substantially at the meeting of the bases of the two truncated cones, so that the side frame has a bearing on the box only at its middle portion, thus permitting the box to rock slightly on its central zone, as above described, and the load is carried entirely at the central transverse zone of the box (the box having no direct contact with the seat in the side frame at its end portions,) as a result of which the load is uniformly distributed over the entire length of the axle journal.

In the design illustrated in Figs. 1 to 9, 45 the usual wedge or key is omitted, and the journal bearing or brass 14 fits directly against the roof of the box. This journal bearing is held in place by being provided midway of its length with upwardly projecting portions or lugs 16 which extend into pockets or recesses 17 formed in the roof of the box at its central portion, and which recesses are made possible because of the upwardly projecting portion or lug 55 60 65 70 75 80 85 90 95 100 105 110 115 120 125 130

13 on the top of the box. This brass has both its inner and outer surfaces of semi-circular shape in cross section, but with the upper surface struck from a center farther out than its inner surface, and consequently eccentric thereto and providing a bearing thicker at its longitudinal middle portion than at its edge portions.

An emergency connection between the box and side frame is provided by means of 85 a pin 18 extending through perforated lugs

19 on the side frame and similar lugs 20 on the journal box. The holes in these lugs are somewhat larger than the pin so as to permit the box to have the rocking movement above described. Similar emergency connections between side frames and journal boxes have heretofore been provided but at the outer side of the side frame and forward end of the journal box. In the design illustrated, this emergency connection is located 70 75 80 85 90 95 100 105 110 115 120 125 130

at the inner side of a side frame and rear end of the journal box. This is an advantage when the truck side frame is lifted together with the journal box and axle, as it brings the suspension for the journal box and axle more directly over the load than when the emergency connection is located at the outer end of the journal box, as will be apparent.

The journal box illustrated in Figs. 1 to 9 is formed in two separable sections, the line of division being substantially at the horizontal plane of the center of the axle, and said sections are united by means of pins 21 extending through perforated lugs 22 on the top section and similar lugs 23 on the bottom section. If either pin is removed the bottom section will swing downwardly around the other pin as a hinge. The meeting faces of these two sections are formed sinuous, so as to provide grooves or gutters 24 in the bottom section, said faces being so formed that the walls 25 on the inner sides of said grooves are lower than the walls 26 on the outer sides of said grooves in order that the oil which will work into said grooves or gutters will flow into the box rather than to the outside. At the rear or inner end of the box is a dust-guard pocket 27, and because the box is made in two separable sections, this pocket is entirely inclosed, that is, inclosed at the top as well as at the bottom and sides. The grooves or gutters 24 in the bottom section open this dust-guard pocket, and the inner wall 28 of said pocket is lower than the outer wall 29 thereof, so that any oil which flows from the grooves or gutters 24 into the pocket, will flow into the box instead of to the outside.

The journal box is of substantially circular interior section, and consequently the dust-guard pocket 27, as well as the dust guard 30 therein, are circular, which permits said dust guard to rotate to some extent and carry oil, which may accumulate in the bottom of the pocket, all around, so that the oil, together with the dust which naturally is caught by the oil, form a practically tight seal at the rear end of the box. Dust will also be caught by oil which will work into the grooves or gutters 24, and thus form a substantially tight seal along the meeting edges of the two sections of the box. Oil will almost certainly get into the grooves 24 and from the same into the dust-guard pocket, as it will

naturally be carried up by the rotation of the axle and scrapped off from the axle by the lower edge of the brass, from which it will flow by gravity and capillary attraction into the joints between the two sections of the box, and as the oil will collect or hold the dust, a gummy seal will be formed. The dust guard 30 is preferably of fibrous construction, such as being built up from layers of canvas or the like, which can be held by a sheet metal grooved ring 31.

The outer end of the journal box is closed by a circular lid 32 which is united at its center by means of stud 33 to a lever 34 5 hinged to lugs 35 on the top of the box. The lever 34 carries a spring 36 bearing against a cam-faced lug 37 on the journal box,—by means of which the lid will be held either in tightly closed position or in open or elevated position, as is common in journal box lids. This lid is preferably provided on its peripheral edge with a suitable gasket 38, which, also, preferably will be of fibrous construction, such as formed of layers of canvas 10 held by a wire ring 39 which is suitably clamped in the edge of said lid.

The journal bearing or brass 15 at its ends is substantially of semi-circular form, thus bringing it down practically to the center 10 of the axle, and providing about 50% more end thrust bearing than brasses as heretofore constructed, which prevents the brasses from wearing as rapidly as brasses as heretofore made, and increasing the life thereof. With 15 standard journal boxes it is not possible to make a brass of such shape as to come down to the center of the axle as it is impossible to remove the brass if made that large, but with a separable box, such as illustrated and de- 20 scribed, this difficulty is entirely avoided and the brass can be made to extend down on the sides of the axle to or beyond the center.

Fig. 10 illustrates a modification having substantially the same integral side frame as shown in Fig. 1 except that the journal box seat in the end thereof (and the roof of the journal box fitting into said seat) are made substantially angular, that is, of roof shape. The journal box in this form is of 25 the integral or non-sectional type and is secured to the side frame by means of rivets 40 and 41, as in my co-pending application, Serial No. 71,779, filed January 12, 1916. The rivet 41 passes through the web of the tension member, and to permit access thereto, the web of the compression member is provided with an opening 42. The inner ends of the rivets extend into pockets 43 formed in the upper angles of the journal box. This 30 form of journal box is designed to be used with the standard wedges and brasses, being provided on its side walls with inwardly projecting lugs 44 to hold the wedges and brass. Preferably also the lower portion of the 35 journal box is tied to the central portion of

the side frame by means of a bar 45, which bar is riveted to a lug 46 on the bottom of the box. Preferably the box will be provided with similar lugs 46 on both sides so as to be interchangeable between the two 70 ends of the side frame.

Both forms of side frame illustrated are of the integral cast type provided at their end portions with seats for the journal box and with the parts so designed that the neutral axes of the tension and compression members intersect directly above the center of rotation of the axle, thereby bringing the load directly above the point of support and thereby avoiding bending stresses in the arch 75 bars due to an eccentric support of the load on the axle center. In the form shown, Figs. 1 to 9, the vertical height of the journal box is materially reduced over standard types, as a result of which the ends of the side frame 80 are carried low, resulting in better stress conditions in the side frame.

What I claim is:—

1. A railway car truck side frame of the arch bar type formed as an integral casting 90 comprising a compression member and a tension member each of I-beam cross section having the web horizontal and the flanges vertical.

2. A railway car truck side frame of the 95 arch bar type formed as an integral casting comprising a compression member and a tension member and provided in their united end portion with a journal box seat, the parts being so arranged that the centers 100 of gravity or neutral axes of the tension and compression members intersect directly above the center of rotation of the axle.

3. A railway car truck side frame of the arch bar type formed as an integral casting 105 comprising a compression member and a tension member each of flanged cross section having the web horizontal and the flanges vertical and provided with a journal box seat in their united end portion, said parts 110 being so arranged that the centers of gravity or neutral axes of the tension and compression members intersect directly above the center of rotation of the axle.

4. A railway car truck side frame of the 115 arch bar type formed as an integral casting comprising a compression member and a tension member each of I-beam cross section having the web horizontal and flanges vertical and provided in their united end portion with a journal box seat, the parts being 120 so arranged that the centers of gravity or neutral axes of the tension and compression members intersect directly above the center of rotation of the axle.

5. A railway car truck side frame of the arch bar type formed as an integral casting 125 comprising a tension member and a compression member each of I-beam cross section having the web horizontal and the 130

- flanges vertical and provided in their united end portion with a journal box seat, the downwardly projecting flanges of the tension member being formed to provide a jacking seat adjacent to the journal box seat.
6. The combination of a truck side frame provided at its end with a reentrant journal box seat and with a recess in the upper portion of said seat extending longitudinally of the side frame and a journal box loosely fitting said seat and having a horizontal portion on its top extending transversely of the journal box and having a bearing in the recess in the side frame.
- 10 7. The combination of a truck side frame provided at its end with a reentrant journal box seat of semicircular form and with an upwardly extending recess in the upper portion of said seat extending longitudinally of the side frame and a journal box having a semicircular top and loosely fitting said seat and provided with a horizontal portion projecting above its top and extending transversely of the box and having a bearing in the recess in the side frame.
- 15 8. In combination, a truck side frame provided in its end portion with a semicircular reentrant journal box seat and having a recess extending longitudinally of the side frame and provided with a horizontal top, and a journal box coöperating with said seat and having its upper surface circular in cross section and provided with a projection provided with a horizontal top having a bearing in the recess in the side frame.
- 20 9. In combination, a truck side frame provided in its end portion with a semicircular reentrant journal box seat and having a recess extending longitudinally of the side frame and provided with a horizontal top, and a journal box coöperating with said seat and having its upper surface circular in cross section and provided with a vertical projection located midway of the length of the journal bearing in the box and provided with a horizontal top having a bearing in the recess in the side frame.
- 25 10. In combination, a truck side frame provided in its end portion with a semicircular reentrant journal box seat with a recess arranged longitudinally of the side frame and extending above said seat and provided with a horizontal top, and a journal box having its upper surface circular in cross section and coöperating with the journal box seat and provided with a transverse lug projecting above its circular top and having a horizontal top contacting with the horizontal top wall of the recess in the side frame.
- 30 11. In combination, a truck side frame provided in its end portion with a semicircular reentrant journal box seat, and a journal box coöperating with said seat and having the upper surface of its top circular in cross section, and being larger at its middle zone that at its ends and contacting with the journal box seat at its middle zone only.
- 35 12. The combination of a truck side frame provided at its end portion with a journal box seat, a journal box in said seat and provided on its top with a higher portion forming a bearing against said side frame, and a loose emergency connection between said frame and box.
- 40 13. The combination of a truck side frame provided at its end with a journal box seat, a journal box in said seat, and a lug and pin connection between the frame and box at the rear end of said box.
- 45 14. A railway car truck side frame of the arch bar type formed as an integral casting, in combination with a journal box having a curved top portion, said side frame having the neutral axes of its tension and compression members extended to a meeting point vertically over the center of rotation of the axle, the said neutral axes of the tension member passing close to the curved top of the journal box.
- 50 15. A railway car truck side frame of the arch bar type formed as an integral casting comprising a compression member and a tension member each of I-beam cross section having the web horizontal and the flanges vertical, the web of the tension member extending under the central portion of the frame in the form of a circle or catenary curve.
- 55 16. A railway car truck side frame of the arch bar type formed as an integral casting comprising a compression member and a tension member each of flanged cross section having the web horizontal and the flanges vertical and provided with a journal box seat in their united end portion, said parts being so arranged that the centers of gravity or neutral axes of the tension and compression members intersect directly above the center of rotation of the axle, the web of the tension member extending under the central portion of the frame in the form of a circle or catenary curve.
- 60 In testimony whereof, I have hereunto set my hand.
